UNITED STATES PATENT OFFICE.

JONAS M. FELGER, OF RICHMOND, VIRGINIA.

BOTTLE-WASHING MACHINE.

1,005,110.

Specification of Letters Patent.

Patented Oct. 3, 1911.

Application filed November 26, 1910. Serial No. 594,387.

To all whom it may concern:

Be it known that I, JONAS M. FELGER, of Richmond, in the county of Henric^o and State of Virginia, have invented certain new and useful Improvements in Bottle-Washing Machines; and I hereby declare that the following is a full, clear, and exact description thereof, reference being had to the accompanying drawings, which form part of this specification.

This invention is a novel machine for washing bottles; and is especially designed for use in dairies for cleansing milk bottles in the crates.

The invention comprises mechanism whereby a crate of bottles may be inserted in the machine and in its traverse therethrough each bottle in the crate will be filled with water, soaked, and then washed inside and outside without being removed from the regular filling crate; and the crate of clean bottles can be removed from the machine ready for the filling operation; the washing of all the bottles in the crate being accomplished simultaneously and without any manual handling thereof.

I will describe a machine that embodies the invention,—and which is illustrated in the accompanying drawings,—and will summarize in the claims the novel features thereof and combinations of parts therein, for which protection is desired; but the invention is not restricted to the particular form, proportion, or construction of details, of the machine shown in the drawings.

Figure 1 is a side elevation of the complete machine. Fig. 2 is an enlarged front end elevation thereof. Fig. 3 is a top plan view of Fig. 2 partly broken away. Fig. 4 is a transverse section on the line 4—4, Fig. 2, looking downward. Fig. 5 is an enlarged vertical section through one of the interior brush operating shafts and related parts. Fig. 6 is a detail transverse section on line 6—6, Fig. 2. Fig. 7 is a bottom plan view of one of the bottle plugs. Fig. 8 is an enlarged detail view, illustrating the means of presenting the bottles to the brushes.

The machine shown in the drawings has four uprights 1 which are attached to a base 1^a and which are connected at their upper ends by two plates, 1^b, 1^c, superposed one above the other, which carry the brush operating devices, and other parts of the mechanism. Journaled in these plates 1^b, 1^c,

are a number of vertically disposed tubular shafts 2, see Fig. 5, to each of which is connected—as hereinafter explained—a brush 2^k which washes the interior of the bottles. The shafts 2 correspond in number with the number of bottles which the crates contain: For example if the crates contain twenty bottles, then twenty shafts 2 are employed; so spaced apart that when the crate is properly inserted in the machine each bottle in the crate will come directly under a corresponding shaft 2. As shown there are twenty shafts 2 arranged in four parallel rows of five each extending longitudinally of the machine.

On the upper end of each shaft 2 is keyed a gear 2^a; and the adjacent gears 2^a in two adjacent transverse rows of shafts 2 (see Fig. 3) mesh with worms 3^a on shafts 3 journaled in bearings 3^b on the plate 1^c, and extending between the rows of shafts 2, see Fig. 3. Each shaft 3 carries five worms 3^a which operate ten interior bottle-brushes attached to as many shafts 2. Each shaft 3 is provided at one end with a broad loose pulley 3^c beside which is a narrow fast pulley 3^a; and said pulleys can be operated by a single belt, running under the pulleys on shafts 3 and over the pulleys on shaft 6, and belted to any suitable driving pulley, not shown, so that by shifting the one belt the shafts 3 can be simultaneously put into or out of operation at the will of the operator.

Telescoped within the lower part of each shaft 2 is a tube 2^e which has a slot 2^b traversed by a pin 2^c, so that tube 2^e must rotate with the shaft 2 but can slide therein. The tube 2^e is normally projected by means of a helical spring 2^f interposed between the inner end of the shaft and the pin 2^c by which the pinion 2^a is fixed to shaft 2. Fast within the lower end of tube 2^e is a brush-holder rod 2^h which is provided with grooves 2ⁱ on its side to allow water to descend through the tube into the bottle. This brush-holder 2^h has a socket in its lower end to receive the shank or stem 2^j of a brush 2^k which may be secured to the holder 2^h by a screw 2^m or in any other suitable manner. The brushes 2^k are adapted to wash the interior of the bottles and I shall hereafter refer to them as "interior brushes."

All the interior brushes can be rotated simultaneously; and each interior brush is

yieldable vertically to enable the brush to adjust itself to slight variations in the height of the bottles, or unevenness of the bottle supports in the crates, and thus prevent 5 injury to the bottles by being caught between unyielding surfaces. I do not claim the particular construction of these brushes; which may be of any suitable standard make.

10 The bottles while in the crates are presented to the brushes by means hereinafter described; and while the bottles are being washed internally they are also scrubbed externally by means of brushes 4^k (Figs. 2 15 and 8), which I shall term "exterior brushes",—attached to the lower ends of shafts 4 also journaled in the plates 1^b, 1^c; and there should be one exterior brush shaft 4 intermediate every four interior brush 20 shafts 2 in adjacent rows (see Fig. 4). The exterior brush shafts 4 may be driven by gears 4ⁿ meshing with pinions 2ⁿ on the adjacent shaft or shafts 2 (as shown in Figs. 4 and 5),—the gears 2ⁿ, 4ⁿ being attached 25 to their shafts below the plate 1^c. By this arrangement of brushes each bottle in the 30 crate, (see Figs. 2 and 8) will be scrubbed both externally and internally at the same time.

35 In order that the brushes 4^k may operate effectively on the bottles the latter are rotated during the scrubbing process by the following means: Loosely mounted on the lower end of each shaft 2 below the plate 1^b 40 is a pinion 5 which has a groove 5^a in its hub engaged by a retainer plate 5^b fast to the plate 1^b, (see Figs. 2 and 5) so that the pinion 5 is upheld independently of the related shaft 2. The pinion 5 is also provided 45 on its lower side with a preferably externally threaded hub portion 5^c, to which is attached or screwed a bottle plug 5^d which is tapered on its lower side and is adapted to engage and partly enter the mouth of the 50 bottle B. Each plug 5^d is provided with grooves 5^e in its side to permit water to escape from the bottle; and it is also provided with an interior bore 5^f so that water entering the plug can pass on into the bottle. 55 The pinions 5 on four adjacent plugs 5^d are adapted to mesh with a driving pinion 5^h loosely mounted on an adjacent exterior brush shaft 4, (see Figs. 4 and 8). Each pair of adjacent pinions 5^h (see Fig. 4) 60 may be rotated by means of a worm 5ⁱ attached to a shaft 5^j extending transversely through the machine and journaled in bearings 1^l attached to the underside of plate 1^b; and shaft 5^j is provided with a pulley 6^k on one end which is driven by a belt 5^l 65 from a pulley 6^l on a transverse shaft 6 journaled in bearings 6^b attached to the upper plate 1^c; and said shaft 6 is provided at the end adjacent pulleys 3^c, 3^d with a fast pulley 6^d and a loose pulley 6^c, which are ar-

ranged the reverse of the pulleys 3^c, 3^d (see Figs. 2 and 3) so that when the driving belt is shifted to engage fast pulleys 3^d it engages loose pulley 6^c, and when shifted to position to engage loose pulleys 3^c it engages 70 fast pulley 6^d. When shifted to an intermediate position it would only engage the loose pulleys 3^c, 6^c.

The bottles B are yieldingly pressed upward, (by means hereinafter described) 75 during the scrubbing operations so that their mouths engage the plugs 5^d with sufficient force to cause the bottles to turn with the plugs as the latter are rotated by the driving gearing above described. It will 80 be seen that by the means described the bottles are caused to rotate slowly in a direction contrary to the rotation of the rapidly rotating interior brushes during the 85 washing operations while the exterior brushes rotate oppositely to the interior brushes. Clean water is supplied to the bottles through the shafts 2, tubes 2^c and plugs 5^d, from a tank T, supported upon the plate 1^c, to which water is supplied in 90 any suitable manner, and from which the water is admitted through tubes t into the upper end of each tubular shaft 2.

The bottles to be washed are arranged in ordinary bottomless crates C (see Fig. 8) 95 which are divided by metal rods or bands into compartments or stalls for the bottles; and the bottles are supported in the compartments upon smaller intersecting wires, so that the bottles can be readily engaged by lifting devices operating upwardly from below the crate and between the intersecting wires. This form of crate is well known and does not need any further explanation or illustration herein. In the machine shown each crate should contain twenty compartments, for as many bottles, such compartments corresponding in axial arrangement to the arrangement of the interior brush-actuating shafts 2. 100 105 110

A crate C filled with bottles is first placed upon a pair of horizontal guide bars 9 mounted at one end of the machine and then slid inwardly beneath a tank T', which may be constructed like tank T, provided with a series of depending tubes t' so that while the bottles in one crate are being washed, the bottles in another crate may be filled with water and allowed to soak. Any overflow from the tanks or bottles during the 115 operation of the machine can be directed into a receiving tank T² from which the water may be carried off by suitable means to a sewer or drain.

The crate of water-filled bottles is slid 120 from beneath the tank T' onto a vertically movable platform 7 (Figs. 1—2—8) which is provided with eyes 7^a at its corners by which it is guided upon the uprights 1. This platform can be raised and lowered 125 130

at the proper times by means of cams 7^a on a shaft 7^p journaled in bearings upon the base 1^a (Figs. 1 and 2); and each of said cams operates against a roller 7^a attached to a bar 7^t, provided with grooved rollers 7^s by which it is guided to move vertically between adjacent uprights 1; the bars 7^t being connected by bars 7^t to the platform 7 so that the cams 7^a cause the reciprocation of platform 7. Beneath the platform 7 is a second vertically movable platform 7^b, which is provided with eyes 7^c guided upon uprights 1. The platform 7^b may also be raised and lowered by means of pitmen 7^d pivotally connected to the sides of the platform 7^b (see Fig. 2), and also to the cams 7^a. The platform 7^b has a greater extent of vertical movement than platform 7 for a purpose hereinafter shown. Movable with the platforms 7, 7^b, are a series of bottle lifting rods 7^e, which are guided in openings in the platforms 7, 7^b, and are normally projected upwardly by means of springs 7^f interposed between the platform 7^b and collars 7^g on the rods 7^e (see Fig. 8). The upward movement of these rods may be limited by collars 7^h thereon below platform 7^b.

The weight of the loaded crate and the platforms 7, 7^b may be substantially counterbalanced by weights W which are connected by cables w to the platform 7^b; said cables running over suitable guide pulleys w' (see Figs. 1 and 2).

The shaft 7^p may be driven intermittently, so as to operate the cams 7^a in the proper manner and time, by means of a dwell gear 8 (Fig. 1) meshing with a dwell gear 8^b fast to a shaft 8^a suitably journaled in bearings on the base of the machine, and which in turn is driven by a pinion 8^c meshing with a worm 8^d on a shaft 8^e which is substantially vertical, and is journaled in suitable bearings 8^f, 8^g respectively attached to the base 1^a and to the bracket 6^p. Shaft 8^e is driven by means of a bevel gear 8^j on its upper end meshing with a bevel gear 6^j on the shaft 6. The gears 8 and 8^b have related dwell portions 8^a and 8^b so proportioned and located that during each rotation of the shaft 8^a an intermittent motion will be imparted by said gears to the shaft 7^p from the continuously driven shaft 8^e. The dwells of gears 8, 8^b are so proportioned that the bottles will be held stationary after presentation to the scrubbing brushes long enough to be thoroughly scrubbed thereby.

At the end of the bottle scrubbing operation the platforms 7, 7^b are lowered to the position shown in Fig. 8, and then the crate 60 of washed bottles is run out upon stationary guide rails 9^a at the end of the machine opposite rails 9, the platform 7 being then lowered into position substantially flush with rails 9, 9^a, so that a crate of water 65 filled bottles may be slid in upon the crate

supporting rails 7^o attached to platform 7, (see Fig. 8). This can be done while one of dwells 8^a on the gear 8 is in engagement with a corresponding dwell 8^c on gear 8^b. Then the gears 8, 8^b impart motion to the shaft 7^p, 70 and cams 7^a, and the platforms 7, 7^b are raised. As the platforms 7, 7^b rise cams 7^a cause platform 7^b to approach toward the platform 7 and this causes spring 7^f to project rods 7^e above the platform 7; and these 75 rods 7^e entering the lower portion of the crate engage the several bottles therein and raise these bottles partially out of the crate, as shown in dotted lines in Fig. 8,—and cause them to yieldingly engage with the 80 plugs 5^a. After these parts are raised to the position shown in full lines in Figs. 1 and 2, and dotted lines in Fig. 8, the shaft 7^p is stopped by the dwells in gears 8, 8^b coming into engagement; and while the 85 parts are thus stopped each bottle is rotated as above described, and scrubbed by the more rapidly rotating exterior and interior brushes 2^k, 4^k. At the end of the dwell the platforms 7, 7^b and crate of washed bottles 90 are lowered; the rods 7^e withdrawing from the crate (as shown in full lines Fig. 8) and the bottles dropping away from the brushes; so that the crate of washed bottles can be slid out upon the guide rails 9^a 95 while a crate of soaked bottles is slid upon the guide bars 7° of platform 7 ready to be subjected to the action of the brushes.

The machine is entirely automatic and no shifting of the belt is necessary in the ordinary operations thereof, as the dwell gears regulate the time of scrubbing the bottles, and also the time for raising and lowering the crates of bottles; and the operator simply has to feed crates of unwashed bottles to the 100 machine and remove the crates of cleansed bottles therefrom.

In actual practice after the bottles leave the washing apparatus they pass on to rinsing and sterilizing devices, not shown in the 110 drawings, as they form no part of the present invention.

What I claim is:

1. In a bottle washing machine, the combination of a series of vertically disposed 115 parallel brushes, gearing for simultaneously rotating all these brushes, a crate support below the brushes adapted to support a crate of bottles, means for moving the crate support toward the brushes, and means for 120 yieldingly raising each bottle in the crate during the scrubbing operation.

2. In a bottle washing machine, the combination of a series of vertically disposed parallel brushes adapted to scrub the interior 125 of bottles, gearing for simultaneously rotating all these brushes, a platform below the brushes adapted to support a crate of bottles, means for moving the platform and crate vertically toward the brushes so 130

cause the latter to enter the bottles, and means for yieldingly raising each bottle in the crate during the scrubbing operation.

3. In a bottle washing machine, the combination of a series of vertically disposed parallel brushes adapted to scrub the interior of bottles, gearing for simultaneously rotating all these brushes, a platform below the brushes adapted to support a crate of bottles, means for moving the platform and crate vertically toward the brushes so as to cause the latter to enter the bottles, and means for yieldingly raising each bottle in the crate during the scrubbing operation; with means for rotating the bottles on their own axis during the scrubbing operation.

4. In a bottle washing machine, the combination of a series of vertically disposed parallel brushes, and means for rotating the same, a pair of movable platforms below the brushes, means for reciprocating said platforms to and from the brushes, and for giving one of said platforms a greater extent of travel than the other; the upper platform being adapted to receive a crate of bottles and raise the crate so as to simultaneously present all the bottles therein to the brushes, and yieldable spring pressed rods movable with the lower platform and adapted to project through the upper platform into the crate and raise all the bottles therein and hold them in yielding contact with the brushes during the scrubbing operation.

5. In a bottle washing machine, the combination of a series of vertically disposed parallel interior brushes, and means for rotating the same; a pair of movable platforms below the brushes, means for reciprocating said platforms to and from the brushes and giving one of said platforms a greater extent of travel than the other; and yieldable spring pressed rods movable with the lower platform and adapted to project through the upper platform into a crate of bottles placed thereon and simultaneously raise all the bottles in the crate into yielding contact with the brushes during the scrubbing operation; with means for rotating the bottles while they are being scrubbed.

50 6. In a bottle washing machine, the combination of a series of vertically disposed parallel interior brushes, and means for rotating the same; a pair of movable platforms below the brushes, means for reciprocating said platforms to and from the brushes and giving one of said platforms a greater extent of travel than the other, the upper platform when lowered adapted to receive a crate of bottles, and yieldable spring pressed rods movable with the lower platform and adapted to project through the upper platform into the crate and raise the bottles therein and hold them in yielding contact with the interior brushes during the scrubbing operation; with a second

series of brush holding shafts parallel with the interior brush shafts; brushes attached to the second series of shafts adapted to scrub the exterior of the bottles while the interior brushes are operating thereupon; means for rotating the exterior brushes, and means for rotating the bottles while they are being scrubbed.

7. In a bottle washing machine, the combination of a series of vertically disposed parallel brushes adapted to scrub the interior of bottles, gearing for simultaneously rotating these brushes, a platform below the brushes adapted to support a crate of bottles, means for raising the platform and crate so that the brushes can simultaneously enter the bottles, and means for yieldingly raising each bottle in the crate during the scrubbing operation, the bottles being independently yieldable; with a series of brushes adapted to scrub the exteriors of the bottles while the interior brushes are operating thereupon; and means for rotating the exterior brushes.

8. In a bottle washing machine, the combination of a series of vertically disposed parallel brushes adapted to scrub the interior of bottles, gearing for simultaneously rotating these brushes, means for raising a crate of bottles toward said brushes so as to cause the latter to enter the bottles, and means for independently raising each bottle in the crate and holding it in yielding contact with the brush during the scrubbing operation; with a series of brushes adapted to scrub the exterior of the bottles while the interior brushes are operating thereupon, and means for rotating the exterior brushes; with means for rotating the bottles on their own axes during the scrubbing operation.

9. In a bottle scrubbing machine, the combination of a bottle crate support, a series of vertically disposed brush shafts thereover, brushes yieldably attached to the lower end of said shafts, a bottle-plug loosely mounted on the lower end of each shaft, means for independently but simultaneously yieldably raising all the bottles in the crate into contact with the plugs, and means for causing the plugs to positively rotate the bottles contrary to the brushes while the brushes are operating thereupon.

10. In a bottle scrubbing machine, the combination of a bottle crate support, a series of vertical shafts thereabove, brush holding shafts yieldably attached to the lower ends of said vertical shafts, a bottle-plug loosely mounted on the lower end of each vertical shaft above the brushes; means for simultaneously raising all the bottles in the crate into contact with the plugs and for yieldingly holding each bottle in contact with its plug so that the brushes may operate upon the interiors of the bottles; and means for causing the plugs to positively

rotate the bottles oppositely to the brushes while the brushes are operating thereupon.

11. In a bottle scrubbing machine, the combination of a bottle crate support, a series of vertical shafts thereabove, brush holding shafts yieldably attached to the lower ends of said vertical shafts, a bottle-plug loosely mounted on the lower end of each vertical shaft above the brushes; means for simultaneously raising all the bottles in the crate into contact with the plug and for yieldingly holding each bottle in contact with its plug so that the brushes may operate upon the interiors of the bottles, the bottles being independently yieldable; and

means for causing the plugs to positively rotate the bottles oppositely to the brushes while the brushes are operating thereupon; with a set of brushes adapted to scrub the exterior of the bottles simultaneously with the action of the interior brushes thereon, and means for rotating the exterior brushes.

10 In testimony that I claim the foregoing as my own, I affix my signature in presence of two witnesses.

JONAS M. FELGER.
